H. E. WINANS.
SHELL.
APPLICATION FILED JAN. 31, 1920.

1,421,882.

Patented July 4, 1922.

Inventor—
Henry E. Winans,
by Cook & McCaulay, Atty.

UNITED STATES PATENT OFFICE.

HENRY E. WINANS, OF BELLEVILLE, ILLINOIS.

SHELL.

1,421,882.

Specification of Letters Patent. Patented July 4, 1922.

Application filed January 31, 1920. Serial No. 355,297.

To all whom it may concern:

Be it known that I, HENRY E. WINANS, a citizen of the United States of America, a resident of Belleville, in the county of St. 5 Clair and State of Illinois, have invented certain new and useful Improvements in Shells, of which the following is a full, clear, and exact description, reference being had to the accompanying drawings, forming a 10 part of this specification.

This invention relates to improvements in shells, and more particularly to an attachment for shells adapted for use in choke-bore shot guns. To clearly understand an 15 object of this invention, it should be borne in mind that the bore of a choke-bore shot gun is narrowed near the muzzle to cause concentration of the shot pattern. A "choke" is formed by a more or less abrupt 20 portion at the muzzle, which serves as an abutment for retarding the load, the wadding being retarded by the peculiar action of the choke on the shot charge, to permit the escape of the shot at a point some distance 25 ahead of the wadding. While the wadding is retarded in the "choke", the body of shot continues in motion under the momentum it has acquired from the force of the explosion, and gaining "lead" over the wadding 30 which effectively prevents spread or scatter of the shot. In a cylinder bore shot gun, the wadding behind the shot escapes freely so as to engage and spread the shot immediately after the latter escapes from the 35 muzzle, but this is not true of a choke-bore gun wherein the wadding is retarded so as to escape some distance behind the shot.

It is sometimes desirable to spread or scatter the shot passing from a choke-bore 40 gun, and an object of my invention is to provide a simple means whereby this result is accomplished.

Briefly stated, the invention comprises a very simple connecting device associated 45 with the shot and wadding in a particular manner, so as to compel the shot-driving wadding to follow the shot while the charge is passing through the bore of the gun. If this wadding escapes with, or immediately 50 behind, the shot it will serve as a spreader for scattering the shot in a manner well understood in this art.

Fig. I is a side elevation, partly in section, illustrating a shot-gun shell equipped 55 with a connecting attachment embodying the features of this invention.

Fig. II is an end view.

Fig. III is a transverse section.

To illustrate the invention I have shown a shot-gun shell comprising a cup or case A 60 crimped at its outer end to provide an in-turned flange 1 engaging a stiff card-wad 2, known as the top shot wad. The shell also contains felt wads 3, a card-wad 4, powder 5 engaging said wad 4, and a body of shot 65 between the wads 2 and 3.

When the shell is fired in a gun, the pressure resulting from explosion of the powder acts primarily on the card-wad 4, and this pressure is transmitted through the felt wads 70 3 to the body of shot 6 and thence to the card-wad 2. It will, therefore, be understood that either of the wads 3 may be termed "a shot-driving member" and the card wad 2 may be termed "a shot-driven 75 member".

If the wads 2 and 3 are connected together by means of a connecting device adapted to travel through the bore of the gun with the shot, the wads 3 will follow the shot and 80 serve as a spreader for scattering the shot escaping at the muzzle of the gun.

As an illustration of a very simple and otherwise desirable form of the invention, I have shown a connecting member consisting 85 of a wire spear 7 provided with barbs 7' near its sharp pointed inner end, and having a large head 8 at its outer end. This connecting member is preferably located at the longitudinal center line of the shell, and its 90 barbs 7' are securely anchored in the felt wadding 3, while its head 8 engages the stiff card wad 2. The shot-driving wads 3 are thus connected to the shot-driven wad 2.

When the shell is fired in a choke-bore 95 gun, the shot will escape through the choke and at this point the shot, moving on by momentum, will place the connecting member 100 7 under tension, with the result of pulling the wads 3 through the "choke" and compelling said wads to follow the shot to the muzzle of the gun, where said wads 3 will serve as a spreader for scattering the shot.

Another important advantage of the simple and inexpensive connecting spear herein 105 shown lies in the fact that it can be very easily driven into an ordinary shell. A sportsman using a choke-bore gun can use the ordinary shells whenever the shot is to be concentrated in a relatively small area; 110 and when it is desirable to spread the shot the same type of shell may be easily equipped

with the connecting spear. It will now be understood that this invention enables a choke-bore gun to be used when it is desired to spread the shot, and the simple connecting spear enables an ordinary shell to be easily and quickly converted into a special shot-spreading shell.

I claim:

1. A shell containing a shot-driving wad, a shot-driven member, a body of shot between said shot-driving wad and shot-driven member, and non-fusible means for connecting said shot-driving wad to said shot-driven member.
2. A shell containing a shot-driving wad, a shot-driven member, a body of shot between said shot-driving wad and shot-driven member, and a non-fusible connecting member passing through the body of shot to connect said shot-driven member to said shot-driving wad.
3. A shell containing a shot-driving wad, a shot-driven wad, a body of shot between said wads, an explosive whereby said shot and wads may be discharged from the shell, and non-fusible means for anchoring said shot-driven wad to said shot-driving wad, so as to compel the shot-driving wad to follow the shot.
4. A shell containing a shot-driving wad, a shot-driven wad, a body of shot between said wads, an explosive whereby said shot and wads may be discharged from the shell, and non-fusible means for anchoring said shot-driven wad to said shot-driving wad, so as to compel the shot-driving wad to follow the shot, said means comprising a connecting member extending through said shot-driven wad and anchored in said shot-driving wad.
5. A shell containing a shot-driving wad, a shot-driven wad, a body of shot between said wads, an explosive whereby said shot and wads may be discharged from the shell, and means for anchoring said shot-driven wad to said shot-driving wad, so as to compel the shot-driving wad to follow the shot, said means comprising a connecting member extending through the body of shot and having a head engaging the outer face of said shot-driven wad and also having an anchor whereby it is secured to said shot-driving wad.
6. A shell containing a shot-driving wad, a shot-driven member, a body of shot between said shot-driving wad and shot-driven member, and means for connecting said shot-driving wad to said shot-driven member, said means comprising a wire-like spear passing through the body of shot and having a head engaging the outer face of the shot-driven member and also having a pointed end provided with a barb anchored in said shot-driving wad.
7. A shot gun shell containing a shot-spreading attachment of the character described, comprising a barbed connecting spear adapted to be driven through the body of shot and anchored in the wadding behind the shot.
8. In combination with a shell, a shot-spreading attachment comprising a shot-driven head provided with a barbed connecting spear adapted to be driven through the body of shot in the shell.

In testimony that I claim the foregoing I 75 hereunto affix my signature.

HENRY E. WINANS.
